CLOCK

Gustave F. Mattman, Cincinnati, Ohio, assignor
to The Cincinnati Advertising Products Company, Cincinnati, Ohio, a corporation of Ohio

Application August 9, 1935, Serial No. 35,507

4 Claims. (Cl. 58—56)

This invention relates to a clock of novel structure and pleasing appearance.

An object of the invention is to provide a clock in which modern lines and novel effects are achieved through new and effective means of structure.

Another object is to provide a clock of the kind described which may be produced very simply and efficiently and at a minimum of cost.

10 These and other objects are attained by the means described herein and disclosed in the accompanying drawing, in which:

Fig. 1 is a front elevational view of a clock constructed in accordance with the present invention.

Fig. 2 is a cross sectional view taken substantially on the line 2—2 of Fig. 1, the clock unit proper being shown conventionally.

The effectiveness and utility of glass in the production of various types of devices has been increasingly appreciated, particularly in connection with the manufacture of various household articles, which in accordance with modern trends in design and visual effect, are constructed with

25 simple lines, smooth sheer surfaces, and the like. In the present invention glass is adapted to these modern ideas in the production of a clock in which the clock face appears centrally of a transparent glass body to produce an article of

30 pleasing and unusual appearance. With reference to the drawing, the clock body consists of an integral sheet of glass 5, preferably transparent, and formed, by suitably bending along a transverse area as at 6, to provide a base 7 adapted to be disposed flat on a suitable supporting surface, and an upright section 8 supported by said base. The two sections 7 and 8 of the formed sheet are preferably disposed relative to one another at an angle of less than ninety

40 degrees so that the outer surface of the section 8, which is to support the clock unit, may be conveniently observed.

Provided centrally on the front surface of section 8, i. e., on the surface thereof remote from 45 the base 7, is an opaque clock face 9, preferably dark in color, and provided around its edge with clock face numerals 10. These numerals may be formed of a coloring material providing suitable contrast with the clock face 9 so as to stand out distinctly. In the present disclosure, these numerals are shown as cut, such as by sand blasting into the front face of the section 8, as shown at 50 11. The sand blasting results in producing numerals which have a translucent appearance 55 rather than transparent, to provide suitable con-

trast with the clock face 9 and likewise with the transparent section 8 of the clock body.

Attached to the rear surface of the section 8, and disposed behind the opaque clock face 9, is a suitable clock mechanism 12 which is invisible from the front of the clock. Associated with the clock face 9 and operatively connected with the clock mechanism 12 is a pair of clock hands 13 which may be constructed of such material and design as to harmonize with the remainder of the structure to produce a harmonious unit. The hands, for example, may be formed of polished chromium so as to contrast effectively with the dark opaque face 9.

The rear edge of the base 7 may have attached thereto, such as by cementing, a glass block 14 providing a stabilizing and counter weight.

It is apparent that the clock above described may be produced very efficiently and at a minimum of manufacturing cost and that, at the same time, an article of distinctive modern design and appearance may be produced.

What is claimed is:

1. As a new article of manufacture, a clock comprising a body consisting of an integral sheet 25 of transparent glass formed to provide a base adapted to be disposed flat on a supporting surface and an upright section supported by said base, an opaque clock face provided on the upright section, a clock mechanism attached to the 30 upright section behind the clock face, and clock hands associated with the clock face and operatively connected with the clock mechanism.

2. As a new article of manufacture, a clock comprising a body consisting of an integral sheet 35 of glass bent transversely to provide two sections disposed relative to one another at an angle of less than 90°, one of said sections forming a base adapted to be disposed flat on a supporting surface and the other section forming an upright 40 supported by the base, an opaque clock face on said upright section and visible from the side remote from said base, a clock mechanism attached to the upright section behind the clock face and on the surface of said section adjacent said base, 45 and clock hands associated with the clock face and operatively connected with the clock mechanism.

3. As a new article of manufacture, a clock comprising a body consisting of an integral sheet 50 of transparent glass bent transversely to provide two sections disposed relative to one another at an angle of less than ninety degrees, one of said sections forming a base adapted to be disposed flat on a supporting surface and the other section 55

5 forming an upright supported by the base, a dark opaque clock face on that surface of said upright section remote from said base, the numerals of the clock face being cut in the clock face and into the surface of the glass therebeneath whereby the 10 numerals appear in contrast with the dark clock face, a clock mechanism attached to said upright section behind the clock face and on the surface of said section adjacent said base, and clock hands associated with the clock face and operatively connected with the clock mechanism.

4. As a new article of manufacture, a clock

comprising a body consisting of an integral sheet of transparent glass bent to provide two sections angularly disposed relative to one another whereby the bent sheet is adapted to be stood up on a supporting surface with at least one of said sections disposed in an upstanding position, an opaque clock face provided on said upstanding section, a clock mechanism attached to the upstanding section behind the clock face, and clock hands associated with the clock face and operatively connected with the clock mechanism. 5
